UNITED STATES PATENT OFFICE.

WILLIAM A. LORENZ AND EDWARD E. CLAUSSEN, OF HARTFORD, CONNECTICUT, ASSIGNORS TO ALBERT H. WALKER, TRUSTEE, OF SAME PLACE.

PROCESS OF MAKING PAPER BAGS.

SPECIFICATION forming part of Letters Patent No. 519,916, dated May 15, 1894.

Application filed August 18, 1892. Serial No. 443,360. (No model.)

To all whom it may concern:

Be it known that we, WILLIAM A. LORENZ and EDWARD E. CLAUSSEN, citizens of the United States, residing at Hartford, in the 5 county of Hartford and State of Connecticut, have invented certain new and useful Improvements in Processes of Making Paper Bags, of which the following is a full, clear, and exact specification.

10 This invention is a new and useful process of making such paper bags as that described and shown in Reissued Letters Patent No. 10,083, of April 11, 1882.

Figure 1 is a plan view of a length of tucked paper tube, such as has long been well known in the art of making such bags. Figs. 2 and 3 are an edge and an end view respectively of the blank of Fig. 1. Fig. 4 is a plan view of the blank of Figs. 1, 2 and 3, after the first 15 step of our new process has been performed thereon; and Fig. 5 is a view of the lower edge of Fig. 4. Fig. 6 is a view of the completed bag with both flaps of the diamond folded and pasted down. Fig. 7 is a plan view of 20 the blank of Fig. 1 with various instrumentalities shown in connection therewith. Fig. 8 is a view of the lower edge of Fig. 7. Fig. 25 9 is a plan view of what is shown in Fig. 7, showing the blank partly folded. Fig. 10 is 30 a view of the lower edge of Fig. 9. Figs. 11 and 13 are plan views representing successive 35 stages in the folding operation, and Figs. 12 and 14 respectively are side views thereof. Fig. 15 is a plan view showing the completion 40 of the first step in the folding of the bottom. Fig. 16 is a plan view of what is shown in Fig. 15, excepting that the folding operation is not carried quite as far as in that figure. Figs. 17 and 18 are respectively plan 45 and side views of the blank of Fig. 16, showing instrumentalities for supporting and folding the rear flap of the diamond. Fig. 19 is a plan view of the blank, showing the rear flap folded over upon the bottom. Fig. 20 is 50 a view of the lower edge of Fig. 19. Fig. 21 is a perspective view of the bag blank as folded in Figs. 11 and 12. Fig. 22 is a perspective view of the folded bag blank as it would appear in Fig. 15, were the blank to be released from the forward gripper shown in that figure.

The mode of operation of our new process is as follows: The upper ply of the tucked tube, 1, is folded backward on a line corresponding to the forward edges, 3, 4 and 5, of 55 the plate 2, in such a manner as first to produce a folded blank similar to that produced in Fig. 21, and, without stopping, completing the fold as shown in Fig. 15, which when fully flattened down is like that shown in Fig. 4. 60 This folding is accomplished by instrumentalities in addition to the plate, 2, which are as follows: A front gripper, 6, is arranged in front of the blank, gripping the lower ply, 7, of the tube between the two slits, 8 and 9. 65 A pair of triangular blades, 10 and 11, pivoted on shafts, 12 and 13, are arranged at the sides of the tube and in front of the plate, 2, in such a position that their apexes, 14 and 15, can be swung into the tucks 16 and 17 70 of the tube 1. Attached to the outer ends of the blades 10 and 11 are two clips, 20 and 21, shown open and pivoted to the blades, at 22 and 23. The operation of these instrumentalities in folding the bag blank is as follows: 75 The tucked tube, 1, is placed upon the table, 19, beneath the plate, 2, with enough of its forward end projecting to make the bottom of a bag. The lower ply of the tube is gripped by the gripper, 6, and held to the bed, 19; then 80 the triangular blades, 10 and 11, are swung upon their pivots, 12 and 13, into the tucks 16 and 17, so that the sides 24 and 25 of the blades 10 and 11 correspond in position with the sides 3 and 5 of the plate 2; while the 85 sides 26 and 27, nearly coincide in position with the dotted lines 28 and 29. In this position, and while the plate 2 is in its raised position, the blades 10 and 11 are rocked, with their clip ends upward, on axes corresponding 90 with the sides 26 and 27 of the blades, and also corresponding with the diagonal dotted lines 28 and 29. These blades are shown partly raised in Figs. 9 and 10; which motion of the blades operates to raise the upper plies, 95 30 and 31, of the blank. These plies are raised still farther by the upward swinging motion of the blades 10 and 11, as shown clearly in Figs. 11 and 12. In Fig. 11, however, the upper clip ends of the blades are 100 omitted for greater clearness. In this position the blank assumes the peculiar shape

shown in Fig. 21, where the lower ply, 7, has been held flat, the upper ply, 32, has been bent inward, and the well-known inside triangular folds, 33 and 34, of the bag shown in Reissued Letters Patent No. 10,083 are fully developed, having been stretched flat by the blades 10 and 11, in connection with the plate 2. This plate 2 being cut away at 3 and 5 at an angle of about forty-five degrees, holds the upper plies, 30 and 31, while the paper is being stretched over the edges, 24 and 25 of the blades 10 and 11. When the inside triangular folds, 33 and 34, are fully stretched out, the blades 10 and 11 are rocked backward from the position shown in Figs. 11 and 12, to that shown in Figs. 13 and 14 and then without stopping, to that shown in Fig. 15. During the first part of this backward swing of the blades 10 and 11, the clips 20 and 21 are swung inward against the edges, 24 and 25, of the blades 10 and 11 so as to clip the paper at 35 and 36, thereby holding it during the downward swing of the blades 10 and 11. During this downward swing, the upper plies, 30 and 31 swing inward under the blades 10 and 11, as shown clearly in Figs. 13 and 14. This folding completes the diamond 37, which when fully flattened, is like the diamond 38, in Fig. 4. During the making of the fold just described, the plate 2 may be dropped upon the blank 1, holding it firmly to the bed, 19; or it may be raised slightly therefrom. Paste is then applied to the diamond, as shown at 39, and the bag is then completed by folding over the flap 40, upon the diamond 38, and then folding the flap 41 over upon the flap 40, and pressing it together upon the bottom of the bag, thus completing it, as shown in Fig. 6. By using the front gripper, 6, during the diamond folding of the blank, the forward end thereof will be held flat, but it is not necessary to use this front gripper in connection with the other instrumentalities. In this case, during the folding just described, the blades 11 and 12, with their clips, 20 and 21, are raised and lowered,

in the manner before described, and co-operate with the plate 2 in folding the inside triangular folds and laying them down upon the body of the blank; after which, instead of assuming the diamond form, 37, the blank assumes a box-like form 42. This box-like form may be collapsed into the diamond form by pressing inward and downward the two sides, 43 and 44. A further modification in the process may be made by preventing the rear flap, 40, from being folded down flat during the previously described diamond folding step; this may be done by bringing forward a blade, 45, in the rear of the flap 40, while the blades 10 and 11 are approaching their downward position, as shown in Fig. 16, where, however, the blade, 45, is not shown. It is shown in Figs. 17 and 18, but in those figures the blades 10 and 11 are omitted. When the blade 45 has been brought forward, as shown in Figs. 17 and 18, a creaser-blade, 46, is brought down upon the body of the blank at the folded line, 47, and paste is applied at 48; then the blade 46 is withdrawn, while the blade 45 is pushed forward, folding over the flap 40 as shown in Figs. 19 and 20. The front flap, 41, is then folded over upon the bottom of the blank, and the bag is thus completed.

We claim as our invention—

That process of making a paper bag from a tucked tube which consists in turning the upper plies of each of the tucked sides up substantially at right angles to the body of the tube and to each other upon lines corresponding to the angular edges 3 and 5, thus stretching open the inside triangular folds, then folding those upturned plies and folds down upon the body of the blank producing the diamond form, and then completing the bag by folding the end flaps, all substantially as described.

WILLIAM A. LORENZ.
EDWARD E. CLAUSSEN.
